UNITED STATES PATENT OFFICE

134,814

DESIGN FOR A BIRD HOUSE OR THE LIKE

Lynn W. Hoskins, Knoxville, Tenn.

Application September 5, 1941, Serial No. 103,178

Term of patent 14 years

To all whom it may concern:

Be it known that I, Lynn W. Hoskins, a citizen of the United States, residing at Knoxville, in the county of Knox and State of Tennessee, have invented a new, original, and ornamental Design for Bird Houses or the like, of which the following is a specification, reference being had to the accompanying drawing, forming part thereof.

In the accompanying drawing:

Fig. 1 is a perspective view of a bird house showing my new design;

Fig. 2 is a front elevation thereof; and

Fig. 3 is a side elevation thereof.

I claim:

The ornamental design for a bird house or the like, substantially as shown.

LYNN W. HOSKINS.
